UNITED STATES PATENT OFFICE.

OSBORNE K. FOLLANSBEE, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

OPERATOR'S CHAIR.

1,318,438.

Specification of Letters Patent. Patented Oct. 14, 1919.

Application filed February 7, 1917. Serial No. 147,152.

To all whom it may concern:

Be it known that I, OSBORNE K. FOLLANSBEE, a citizen of the United States, residing at Beverly, in the county of Essex and State of Massachusetts, have invented 5 certain Improvements in Operators' Chairs, of which the following description, in connection with the accompanying drawings, is a specification, like reference characters 10 on the drawings indicating like parts in the several figures.

This invention relates to chairs and particularly to improvements in chairs for the use of operators of machines in factories.

15 An object of this invention is to provide a chair for the above purpose which, while being inexpensive, will be comfortable, convenient; durable and safe.

With a view to producing a safe chair 20 for this purpose, one feature of the invention consists in providing a chair which will fold up toward the machine when the operator arises therefrom, in order to clear the aisle and permit the operators to leave the 25 room hurriedly in case of panic, fire or other accident.

With the object in mind of producing a comfortable and convenient chair, one feature of the invention consists in providing 30 adjustments so that the chair may be positioned toward and from the machine or side- wise and be secured there in order that the operator may be properly located relatively to the machine. Further adjustment is also 35 provided for locating the seat vertically for the same purpose.

The illustrated construction and arrangement are particularly well adapted for embodiment in a chair built principally of 40 metal, such a construction having among other advantages the advantage that it will stand the hard usage to which chairs in factories are subjected.

Other features and objects of the invention 45 will be apparent when the following description and claims are considered in connection with the accompanying drawings.

In the drawings:

Figure 1 is a perspective of the chair when 50 in position for the operator's use.

Fig. 2 is a perspective of the chair in folded position, and

Fig. 3 is a detail, partly in section, of the base portion showing the means for permit-

ting the position of the chair upon the floor 55 to be adjusted and for then securing the chair in such position.

Referring to the drawings in detail, 10 is the base portion of the chair and consists of a casting having a recess 12 in its under 60 side, having supporting sockets 14 for holding the seat-supporting uprights and having a lug 16 with a plurality of holes 17, in one of which is a pivot pin 34, to be referred to later. 65

In order to permit the position of the chair upon the floor to be adjusted, a T-slotted casting 20 is provided, which is fastened to the floor by means of screws 22. Before this piece is secured to the floor, a 70 screw is placed with its head located in the wide portion of the slot and with the threaded portion standing upright to pass through a slot 24 provided in the base portion 10, which slot is located substantially 75 at right angles to the slot in the T-slotted piece. A thumb nut 26 on the screw draws the base portion securely against the floor after the proper location has been determined. By the above construction, a simple 80 and effective means is provided for allowing adjustment of the location of the chair upon the floor.

In each of the sockets 14, uprights 30 are 85 secured. These uprights are of pipe or tubing and have holes near their upper end for receiving a pivot rod 32, to be referred to later. In the construction shown in the drawing, a seat supporting frame or casting 34 is provided, to which a wooden seat 36 90 is secured. However, the seat may be made of any suitable material and, if made of metal, the lugs shown on the seat-supporting frame may be made integral with the seat, in which case the seat-supporting frame 95 would not be used. At the forward end of the frame are two lugs in each of which are a plurality of holes 38 for receiving the pivot rod 32. The pivot rod may be selectively located in any of these holes or pivot 100 locations, to adjust the height of the front of the seat. At the rear of the frame are two lugs having holes 40 for the reception of a pivot rod 42 which connects the seat to the unitary piece of pipe or tubing 44. 105 In the tubing 44 are a plurality of holes 45 for the reception of the pivot rod 42, any set of which may be used to provide adjustment.

for the height of the rear of the seat, corresponding to the adjustment of the front of the seat. This tubing 44 is bent and forms the rear legs of the chair and is extended 5 above the seat to provide a support for the back-rest 46. The back-rest can be clamped to the tubing 44 in any adjusted position by means of the screws 48 passing through the clamping member 50. However, if desired, 10 the chair may be constructed without the back-rest and the tubing then need not extend above the seat.

In order to guide the rear legs and maintain them in the proper position when the 15 chair is folded, a pivot rod 52 passes through holes in the lower portions of the rear legs and to these pivot rods is joined the connection 18, above mentioned. The connection 18 is pivotally connected to the lug 16 20 by means of a pivot pin 54. It will be noted that the pivots 32, 42, 52 and 54 are located in the edges of substantially a parallelepiped and, therefore, when the rear legs are lifted upwardly, they remain in substantially 25 a vertical position and are drawn in close to the uprights 30, while the seat 36 assumes nearly a vertical position. This folded position of the chair is shown clearly in Fig. 2.

30 In order to cause the chair to fold up, when the occupant arises therefrom, a spring 56 is connected to the pivot rod 52 and to a lug 58 depending from the seat-supporting frame. This lug 58 has a plurality of holes 35 60, into any of which the hook of the spring 56 may be inserted in order to adjust the tension of the spring. When the chair is occupied, the spring 56 is extended but, when 40 the occupant arises, the tension of this spring draws the seat and rear legs toward each other and causes the chair to assume the folded position shown in Fig. 2.

In adjusting the height of the seat, a line 45 joining the pivot rods 32 and 42 assumes different angular relations with the floor and, accordingly, the pivot pin 54 should be located in the proper hole in the lug 16 so that a line joining the pivots 52 and 54 will be parallel to a line joining the pivot rods 32 and 42, so that all the pivots will lie in the edges of a parallelepiped and thus prevent any cramping action when the chair is folded.

Having thus described the invention, what 55 is claimed as new and desired to be secured by Letters Patent of the United States is:—

1. A folding chair having, in combination, front legs, supporting means to which the front legs are fixedly secured, a seat connected to the front legs, rear legs connected to the seat, and means for causing the rear legs normally to approach the front legs.

2. A folding chair having, in combination, front legs, supporting means to which 60 the front legs are fixedly secured, a seat piv-

otally connected to the front legs, rear legs pivotally connected to the seat, and means for causing the rear legs normally to approach the front legs.

3. A folding chair, having, in combination, 70 a base portion constructed and arranged to be secured to a floor, uprights fixedly secured to said base portion, a seat pivotally connected to said uprights, rear legs pivotally connected to the seat, connections pivotally joining the rear legs and the base portion and means for causing the chair to fold up when the occupant arises therefrom.

4. A folding chair having, in combination, 80 a base portion constructed and arranged to be secured to a floor, uprights secured to said base portion, a seat pivotally connected to said uprights, rear legs pivotally connected to the seat, said rear legs being composed of a unitary piece of tubing extending above the seat, a back rest adjustably secured to the portion of tubing extending above the seat, connections pivotally joining the rear legs and the base portion and means for causing the chair to fold up when the occupant arises therefrom.

5. A folding chair having, in combination, 85 a base portion constructed and arranged to be adjustably secured to a floor, 90 uprights secured to said base portion, a seat pivotally connected to said uprights, rear legs pivotally connected to the seat, said rear legs being composed of a unitary piece of tubing extending above the seat, a back 100 rest adjustably secured to the portion of tubing extending above the seat, connections pivotally joining the rear legs and the base portion and a spring for causing the chair to fold up when the occupant arises therefrom.

6. A folding chair having, in combination, 105 a T-slotted piece provided with means for securing it to a floor, a base portion with a recess to receive said T-slotted piece in my 110 adjusted location, a slot in said base portion, means passing through the T-slot and the slot in the base portion for clamping the base portion in adjusted location, uprights secured to said base portion, a seat pivotally 115 connected to said uprights, two rear legs pivotally connected to the seat, connections pivotally joining the rear legs and the base portion and means for causing the chair to fold up when the occupant arises therefrom.

7. An adjustable folding chair having, in combination, a base portion, uprights secured to said base portion, rear legs, a seat, pivots for joining the seat to the uprights and to the rear legs, a plurality of pivot 125 locations for said pivots which may be selectively used to adjust the height of said seat, connections between the rear legs and the base portion, pivots for joining the connections to the rear legs and to the base por- 130

tion, and a plurality of pivot locations for the last-mentioned pivots, any of which may be selectively used, according to the adjusted position of the seat, all pivots being selectively located in the edges of substantially a parallelepiped to allow the chair to be folded up when unoccupied.

8. An adjustable folding chair having, in combination, a base portion, uprights secured to said base portion, rear legs, a seat, pivots for joining the seat to the uprights and to the rear legs, a plurality of pivot locations for said pivots which may be selectively used to adjust the height of said seat, connections between the rear legs and the base portion, pivots for joining the connections to the rear legs and to the base portion, a plurality of pivot locations for the last-mentioned pivots, any of which may be selectively used, according to the adjusted position of the seat, all pivots being selectively located in the edges of substantially a parallelepiped to allow the chair to be folded up and means for causing the chair 25 to fold up when the occupant arises therefrom.

9. An adjustable folding chair having, in combination, a base portion, uprights secured to said base portion, rear legs and a back-rest support composed of a unitary piece of tubing, a back-rest, a seat, pivots for joining the seat to the uprights and to the rear legs, a plurality of pivot locations for said pivots which may be selectively used to adjust the height of said seat, connections between the rear legs and the base portion, pivots for joining the connections to the rear legs and to the base portion, a plurality of pivot locations for the last-mentioned pivots, any of which may be selectively used, according to the adjusted position of the seat; all pivots being selectively located in the edges of substantially a parallelepiped to allow the chair to be folded up when unoccupied.

10. An adjustable folding chair having, in combination, a base portion constructed and arranged to be adjustably secured to a floor, uprights secured to said base portion, rear legs, a seat, pivots for joining the seat to the uprights and to the rear legs, a plurality of pivot locations for said pivots which may be selectively used to adjust the height of said seat, connections between the rear legs and the base portion, pivots for joining the connections to the rear legs and to the base portion, a plurality of pivot locations for the last-mentioned pivots, any of which may be selectively used, according to the adjusted position of the seat; all pivots being selectively located in the edges of substantially a parallelepiped to allow the chair to be folded up when unoccupied.

11. An adjustable folding chair having, in combination, a base portion constructed and arranged to be adjustably secured to a floor, uprights secured to said base portion, rear legs and a back-rest support composed of a unitary piece of tubing, a back-rest adjustably secured to the back-rest support, a seat, pivots for joining the seat to the uprights and to the rear legs, a plurality of pivot locations for said pivots which may be selectively used to adjust the height of said seat, connections between the rear legs and the base portion, pivots for joining the connections to the rear legs and to the base portion, a plurality of pivot locations for the last-mentioned pivots, any of which may be selectively used, according to the adjusted position of the seat, all pivots being selectively located in the edges of substantially a parallelepiped to allow the chair to be folded up and a spring for causing the chair to fold up when the occupant arises therefrom.

In testimony whereof I have signed my name to this specification.

OSBORNE K. FOLLANSBEE.
